UNITED STATES PATENT OFFICE.

JOSEPH E. HOLMES, OF WASHINGTON, DISTRICT OF COLUMBIA, ASSIGNOR TO THE AMERICAN AUTOMATIC REFRIGERATING COMPANY, OF RICHMOND, VIRGINIA.

APPARATUS FOR DISTILLING ANHYDROUS AMMONIA.

SPECIFICATION forming part of Letters Patent No. 410,244, dated September 3, 1889.

Application filed December 5, 1888. Serial No. 292,702. (No model.)

To all whom it may concern:

Be it known that I, JOSEPH E. HOLMES, a citizen of the United States, residing at Washington, in the District of Columbia, have invented 5 certain new and useful Improvements in Apparatus for Distilling and Redistilling Ammonia; and I do hereby declare the following to be a full, clear, and exact description of the invention, such as will enable others skilled 10 in the art to which it appertains to make and use the same.

The invention has for its object the distillation or the redistillation of ammonia from water containing it and the preparation of 15 anhydrous liquefied gas in a simple and economical manner; and it consists in the apparatus hereinafter described, and particularly pointed out in the claims.

The following specification, in connection 20 with the accompanying drawings, is sufficiently full and clear to enable those skilled in the art to construct and use said apparatus.

Figure 1 is a plan view; Fig. 2, a sectional 25 side elevation, and Fig. 3 is a transverse section on line $\alpha\alpha$.

A is a tank set in the brick-work of a furnace over a combustion-chamber R, communicating with chimney E⁴. This tank and 30 furnace are intended for heating water for the distillation of ammonia contained in water in the stills B and B'. The tank is longer and wider than the stills to give a free water-space around them, and deep enough to allow 35 a perfect immersion of the stills and yet leave a clear space above, as at T in Fig. 3. I preferably shape this tank so that it may conform to the stills, as indicated in the drawings. The form shown is strong, presents a large 40 heating-surface, and avoids the use and heating of an excess of water. The stills B' are placed in this tank, and may be suspended therein by suitable straps of metal from bars resting on the top of the brick-work, or they 45 may rest on light bars beneath them, or may be supported, as shown, by the pipes D and I, passing from the bottoms of the stills through the wall of the tank. The branch pipes I, which communicate with the bottoms 50 of the stills, serve as inlets for filling or out-

lets for blowing off, stop-cocks b and b' being properly manipulated. Pipe D serves to return drip or water of condensation to the still, as will be hereinafter described. From the top of the stills two vapor-pipes extend upwardly and unite in a pipe C, which is provided with a stop-cock d. At the other end of the stills two branches rise and unite in pipe P, from which is supported the water-glass P' and the pressure-gage O. Beyond the stop-cock 55 d extends a pipe C with a slightly-downward inclination, and by a bend returns to the drip-pipe D, with which it connects slightly above the level of the water in the stills, the length of the pipe C to this point being about 50 fifty feet or more. Vapors from the stills will be so cooled in these pipes by the surrounding atmosphere that all water, grease, or other foreign impurities will be condensed and deposited in drip-pipe D. From this 60 point, where C connects with the drip-pipe, which is about on a level with the top of the stills, there extends in an upward direction a pipe E, which is a continuation of C. It may be extended in any direction and placed in 65 any desired manner, and located either above or under ground or in a running stream. The pipe should be extended and have a large 70 capacity by reason of its great length, so that it may hold a large amount of gas and act as 75 a cooler and condenser, and so that the gas shall reach the stop-cock f cooled to the normal temperature under a pressure near to liquefaction, the pressure being produced by the continued distillation of ammonia. 80

At f, Fig. 1, pipe E is connected with an instrument for transferring gases under pressure, which instrument is fully shown and described in my application for patent filed April 20, 1887, Serial No. 235,515. It is indicated at H, and is composed of two like cylinders, each having one end closed, while the other ends are open and joined by a coupling H², which should be well secured and tight. An elastic sack-like diaphragm has its mouth 85 or edge secured at the coupling, while the free end of this sack-like diaphragm is free to move in either direction. The edge of the open end of the sack, provided, if necessary, with a lateral flange or bend, fits between the 90 95

flanges of the coupling, which, when brought together and properly bolted, secure the diaphragm and leave its main body free to be acted upon by any fluid introduced into H through the connecting-pipes G or G'.

I show in Fig. 1 a steam-boiler N and pump L, connected with the receptacle H by the pipe K, provided with the stop-cock a, and also connected with the before-described o stills by means of the pipe K, having stop-cock b. Stop-cock b', when open, permits waste water to escape through the pipe J. It is not essential that pipes I and D should lead from the under side of the stills, as shown. 5 They may project directly outward from the lower portion of the heads of the stills and pass through the heads of the tank A, the joints being made tight by jam-nuts and asbestos.

o I will now describe the operation of this apparatus, which is based on certain well-known characteristics of ammonia. For example, ammonia is readily absorbed by cold water, and also readily escapes from water when it is heated to from about 120° to 190° Fahrenheit. This property, in connection with its great elasticity and the comparative ease with which it can be compressed from a thousand or more volumes to one, enables it to be handled with 5 ease and safety. Premising that the stills, cocks, pipes, and connections described have been thoroughly built in place and tested to at least two hundred and fifty pounds pressure per square inch, the operation is as follows: The tank A is filled with water and stop-cocks a, b, d, e, f, and g opened and stop-cock b' closed. The pump L is then connected through the medium of a suction-pipe M with a tank or holder containing water of o ammonia in sufficient quantity to fill the receptacle H, and also the two stills B B', up to about the height indicated in Fig. 3, the gage-glass P' serving as a guide. Before pumping, however, it should be known that the diaphragm occupies that part of H nearest the pipe K, that air may be thereby excluded from that end. During the operation of pumping both receptacle H and the stills B B' will be filled, and the pump should then be stopped and the o cocks a b closed. Fire is then kindled in the furnace R and the water surrounding the stills heated and also the ammonia-water in the stills. As the heat increases ammonia in the form of gas is expelled through pipes C 5 and E, pushing before it the air in the pipes until traces of gas may be observed passing out of the pipe beyond the open stop-cock g. To prevent waste of the gas, a pipe or hose should then conduct the mingled air and gas into cold water for a little time until all air 15 is expelled. This water can be redistilled. Stop-cocks f and g are then closed until all ammonia is expelled from the water in the stills, which can be ascertained by opening stop-cock b' and testing the water. This operation being completed and the gas stored in the pipes under pressure, it is shut off

from the stills by closing stop-cock d and the drip-pipe cock e. Blow-off cock b' may now be opened and the waste water in the stills 70 will be forced out by the elasticity of the gas above its surface. When the stills are thus emptied and cock b' is closed and b and f are opened, the water in receptacle H will be forced rapidly into the stills by the gas entering the opposite end of H on the opposite side of the diaphragm therein. The receptacle should be made to hold less than the two stills by twenty or thirty gallons, so that they can never be overfilled. The receptacle H is thus 80 filled with gas at the same pressure as in the pipes, and the diaphragm is changed to the end near the pump and is ready for a new charge when needed. Stop-cock b is again closed, stop-cocks d and e opened, f is closed, 85 and the distillation renewed. While this distillation proceeds pipe C is connected with any strong receptacle for liquefied gas holding any convenient quantity—such as a portable detachable holder for fifty, one hundred, or two hundred pounds; or a holder similar to H may be used and of sufficient capacity to receive five hundred, one thousand, or two thousand pounds for transporting the gas and transferring it to refrigerators 90 or other apparatus for use; or the gas may be forced into mains laid in public streets, which may thus be filled with liquid ammonia-gas. When proper connection is made, the gas in receptacle H (shown in the drawings) is forced 100 into such holder or into mains by opening stop-cock a and stop-cock g and pumping water of ammonia into receptacle H until it is filled and the gas has all left it. When the distillation of a batch is completed, cocks b 105 and b' are closed and cock g also, and cocks d and e are again opened and the distillation is repeated, and so on while the supply of water of ammonia lasts, or until all cylinders, tanks, or pipes are filled with liquefied gas, 110 or as long as desired. During all these operations the fire need not be drawn, and only heat enough need be maintained to keep the water in the tank A near to the boiling-point, care being taken that the 115 water in the tank shall always be above the stills. As there is no cover to the tank, this water can never be heated above the boiling-point, and the water of ammonia in the still being always under some pressure, very little, if any, watery vapor will pass over through pipe C, and such as does will be eliminated while passing down the inclined pipe C C to the drip D, whence it will again mingle with the water in the stills, while the dry gas will pass 120 on and be condensed by the process above described.

I have herein intimated the possibility of carrying liquid ammonia through street-mains, and I shall describe in a separate application for patent novel apparatus for measuring the gas by meter in the expansion-pipes of refrigerators, and also for suspending gas-holders on balance frames and seals, and also

for connecting the absorbing-tanks with pipes returning to the place of distillation, so that all transportation of gas or aqua-ammonia in portable vessels is avoided. As the pumping 5 of the water of ammonia can be done at leisure while the distillation is going on, a small pump throwing ten or fifteen gallons per minute will be ample for works adapted to produce one thousand to two thousand pounds 10 of liquefied gas per day, and the boiler for the pump may be correspondingly small.

In Fig. 4 is shown a plan view, partly in section, and in Fig. 5 a transverse section, of a modification of my apparatus adapted to raise 15 the contents of the still to a regulable temperature and above the boiling-point. The water-tanks A and A' are entirely closed, as represented, and are each provided with a steam-outlet pipe D', which is formed into a 20 coil within the stills B and B', and thence extended outwardly at D² and D³, respectively. These pipes may be connected in any usual manner to allow the tanks to be filled with water through them, or other well-known 25 devices can be provided for this purpose. Safety-valves F provide means for regulating the pressure of steam and indirectly controlling the temperature. It is obvious that such safety-valves might be connected with each 30 steam-outlet pipe.

H' H' indicate branches of outlet-pipe for ammonia communicating with pipes P and I, as before described with reference to Fig. 1.

In operating this apparatus to distill ammonia the larger part of the gas can be expelled at a temperature of about 212° Fahrenheit, or less, free escape of steam from water-tanks being permitted. Toward the end of the distillation a higher temperature 35 may be desirable, and this can be attained by setting the escape or safety valve to open at a pressure of from one to twenty or more pounds. The described arrangement of the steam-coil has the effect to more quickly heat 40 the interior of the ammonia-water and saves both time and fuel.

In Fig. 6 is shown a diagram or plan view of my stills and transfferer connected with vessels for water wherewith to absorb ammonia after its use in an ammonia-expanding 45 vessel, (indicated at T.) In this view parts of the tanks and furnace are omitted. The pump L is shown connected with pipe K and with a return-pipe K'. At the opposite end pipes K and K' connect with K², which by branches connects with four water vessels or 50 absorbing-tanks k', k², k³, and k⁴, and a cock z being provided in each branch. The expanding-vessel T is connected with the several 55 absorbing-vessels by means of the pipe F and its several branches f² and four-way coupling f, each branch having a stop-cock f³.

In operation, ammonia is introduced into a receiver and into an expanding coil or receptacle through pipes E and E', a regulator E² being interposed between the receiver and expander. After its expansion the spent am-

monia is absorbed through pipe F by water in one of the vessels—as, for example, k'—the cocks being suitably operated. The ammonia 70 water thus produced can be pumped into the transfferer H and the pressure produced by the pump in the transfferer used to maintain the pressure of ammonia on the opposite side of the diaphragm therein, this 75 ammonia being simultaneously transferred to the refrigerator upon the movement of said diaphragm. By means of the pump and pipes K K' K² the water from which ammonia has been expelled in the stills can be forced into 80 either of the absorbers, to be returned after it has been saturated by absorption from the refrigerator. Four vessels are preferably provided that the heated water from the stills 85 may have time to cool in one or two of the absorbing-vessels while the others are being used, as before set forth. These vessels should be provided with small vents to allow the passage of air when a vessel is being filled with or emptied of water, which vents will be 90 closed at proper times to prevent the escape of ammonia. In practice two vessels may be used in any structure to be refrigerated, one of which is connected to receive compressed anhydrous ammonia and the 95 other to allow its expansion, an automatic temperature-regulator E² being interposed, substantially as set forth in my patent, No. 357,830, dated February 15, 1887.

It is obvious that more or less than four 100 vessels may be connected with the stills to act as absorbers of ammonia; but the number illustrated is convenient. It is further obvious that the invention may be used either on a small or large scale, the arrangement illustrated in Fig. 6 being suitable for use in a building or block of buildings without the necessity of employing portable holders to convey anhydrous ammonia from the still to the 105 place of use. It will of course be understood that any number desired of refrigerators or refrigerating-rooms or refrigerating-buildings 110 can be supplied through pipe E, suitable fixed holders and other devices being placed in each in any well-known manner; and, if desired, 115 pipe E can be made sufficiently spacious to serve as a holder for any desired number of expanding-coils located in refrigerators and each provided with an automatic regulator, in which case independent or separate holders 120 can be dispensed with; and it is further apparent that the length of pipe E, though it should be considerable, would not be objectionable, for the reason that it is desirable that the freshly-distilled ammonia should be cooled 125 as well as condensed before use.

Having thus described my invention and the mode of operating the same, what I claim as new, and desire to secure by Letters Patent, is—

1. The combination of the water-tank A, the furnace R, the stills B B, located in the tank, the vapor-education pipe C, connected to the drip-pipe D, said drip-pipe and inlet-pipe

K, provided with stop-cocks *b* and *b'*, substantially as and for the purpose described.

2. In combination, the transferring-receptacle H, having a movable diaphragm, the pipe K, provided with the stop-cocks *a* and *b*, the pipe E, the pump L, and the stills B B', as and for the purposes described.

3. In combination, the transferring-receptacle H, the pipe K, vapor-pipe E, provided with the stop-cock *f*, and suitable tanks, holders, or mains communicating with pipe E by a pipe having stop-cock *g*, all as and for the purposes described.

4. The combination of a still, a receptacle provided with a flexible diaphragm, pipes connecting the still with the receptacle on each side of the diaphragm, and stop-cocks, whereby the pressure of gas or vapor in the still can at times desired be made to discharge liquid from the receptacle into the still, substantially as and for the purposes described.

5. The combination of a still, a receptacle divided by a sack-like flexible diaphragm, a pipe communicating with the still and also with the receptacle on one side of the diaphragm, a second pipe communicating with the upper part of the still and with the receptacle on the opposite side of said diaphragm, and stop-cocks and inlets and outlets, substantially as set forth, whereby the still and the receptacle can be filled with ammonia-water and ammonia simultaneously delivered from the other side of the diaphragm, and whereby also ammonia-water can be subsequently expelled from the receptacle and the receptacle simultaneously filled with ammonia on the opposite side of the diaphragm.

6. The combination, with a holder or receptacle for anhydrous ammonia, of stills, a pump,

and a transfferer, as H, the latter being connected with the pump and stills by pipes to receive water from or discharge it into either still, and also to receive ammonia from a still and simultaneously with its reception of water to discharge said ammonia into a holder in a refrigerator or elsewhere without loss of pressure, substantially as specified.

7. The combination, with a holder or receptacle for anhydrous ammonia and with one or more water-vessels connected by pipes having suitable cocks to receive alternately spent ammonia from a vessel for expanding the same, and connected by similar pipes having cocks with stills, of said stills, a pump, and a transfferer, as H, the latter being connected with the pump and stills by pipes to receive water from or discharge it into either still, and also to receive ammonia from a still and simultaneously with its reception of water to discharge said ammonia into a holder in a refrigerator or elsewhere without loss of pressure, substantially as specified.

8. In a distilling apparatus, the combination of a tank or boiler, a still, and a pipe or conduit, the still being located in the water-space of the boiler and the pipe communicating with the steam-space of the boiler and passing through the interior of the still, whereby the latter can be externally heated by water and internally by steam, substantially as set forth.

In testimony whereof I affix my signature in presence of two witnesses.

JOSEPH E. HOLMES.
